UNITED STATES PATENT OFFICE

KENNETH C. FARNSWORTH, OF ATHENS, OHIO

DESIGN FOR A RADIANT GAS HEATER

Application filed October 29, 1929. Serial No. 33,199. Term of patent 7 years.

To all whom it may concern:

Be it known that I, KENNETH C. FARNSWORTH, a citizen of the United States, residing at Athens, in the county of Athens and State of Ohio, have invented a new, original, and ornamental Design for a Radiant Gas Heater, of which the following is a specification, reference being had to the accompanying drawing, forming part thereof.

Figure 1 is a front elevation view of a radiant gas heater, showing my new design.

Figure 2 is a side elevation thereof on a reduced scale.

I claim:

The ornamental design for a radiant gas heater, as shown.

KENNETH C. FARNSWORTH.
